UNITED STATES PATENT OFFICE.

MIKE ZEBICH, OF WOODLAWN, PENNSYLVANIA, ASSIGNOR OF ONE-HALF TO LOUIS FRATRICH, OF EAST PITTSBURGH, PENNSYLVANIA.

PNEUMATIC LOCKING MECHANISM.

1,409,210.

Specification of Letters Patent.

Patented Mar. 14, 1922.

Application filed August 26, 1921. Serial No. 495,614.

To all whom it may concern:

Be it known that I, MIKE ZEBICH, a subject of the Government of Austria, residing at Woodlawn, in the county of Beaver and

5 State of Pennsylvania, have invented certain new and useful Improvements in Pneumatic Locking Mechanism, of which the following is a specification.

This invention relates to locking mechanisms, particularly fluid pressure operated locking mechanisms, especially adapted for railway freight and express cars, but it will be obvious that the device may be employed for any purposes wherein it is found to be 15 applicable.

The primary object of the invention is to provide a locking mechanism of the character described, in a manner as hereinafter set forth, which will permit of the unlocking of the doors supplied therewith only when fluid pressure is available and used to operate the mechanism of the device, therefore freight and express cars having doors provided with such device would be 25 practically immune from marauders when disconnected from the train in transit, which otherwise would be liable to depredations when cars are located at isolated sidings at various times before reaching destinations.

30 Further objects of the invention are to provide a device of the type stated, which is simple in its construction and arrangement, strong, durable and efficient in its use, positive in its action, and comparatively inexpensive to manufacture.

To the accomplishment of these and such other objects as may hereinafter appear, the invention consists of the novel construction, combination and arrangement of parts herein 40 specifically described and illustrated in the accompanying drawing, wherein is shown an embodiment of the invention, but it is to be understood that changes, variations and modifications may be resorted to which come 45 within the scope of the claims hereunto appended.

In the drawing forming a portion of this specification and wherein like numerals of reference designate corresponding parts 50 throughout the several views:—

Figure 1 is a side elevation of a pair of car doors provided with a locking mechanism in accordance with the invention.

Figure 2 is an enlarged sectional view of 55 the device.

Referring in detail to the drawing 1 denotes a car body provided with a pair of sliding doors 2 and 3, respectively.

Fixedly secured to the car structure above and intermediate of the door juncture is a 60 vertically disposed cylinder or casing 4 provided with a bore 5. The lower end of the casing 4 is closed by a cylinder head 6 secured thereto by means of the bolts 7. The upper end of the casing 4 and the lower face 65 of the head 6 are formed with lugs 8 with apertures 9 for the passage of the bolts 10 for securing the casing to the car structure.

Mounted for vertical movement in the casing 4 is a piston 11 to which connects a stem 70 12 the upper end of which is seated slidably in the bearing 13 formed in the top of the casing 4. Fixed to the stem 12 at approximately the central portion thereof, is a disk 14 having a depending peripheral flange 15. 75 A spring 16 is mounted on the stem 12 intermediate of the disk 14 and the top of the casing 4. The action of the spring 16 normally holds the disk 14, and associated parts, in the downward position. 80

Each of the doors 2 and 3 is provided with a latch member 17 which are adapted to project through respective apertures 18 and 19, formed in the casing 4, and engage the flange 15 of the disk 14 for securing the 85 doors in the locked position.

The flanged disk 14 is so positioned in the casing 4 relative to the apertures 18 and 19 that movement of the latch members 17 will automatically shift the disk 14 and engage 90 the flange 15.

The doors can only be unlocked by supplying fluid pressure against the piston 11 through the conduit 20 which communicates with the casing through the port 21. The 95 upward movement of the piston and associated parts is limited by the lugs 22 which are adapted to engage the upper face of the disk 14 and formed on the inner face of the casing 4. A valve 23 is positioned in the 100 conduit 20.

As the device is primarily intended for use in connection with railway cars, air pressure would be used for operating the locking mechanism. Unless a locomotive supplying air is connected with the car the doors of the latter cannot be opened. By operating the valve 23 the air will operate the piston 11 and release the flange 15 from the latching members 17. When air is released 110

the disk 14 and associated parts will return to normal position by the action of the spring 16. Valve 23 is then closed and the device will automatically lock the doors when next they are closed.

It will be obvious that the use of my improved locking device will prevent many depredations as the doors of the cars can only be unlocked when car is connected to train with locomotive supplying the necessary air pressure.

What I claim is:—

1. A locking mechanism for the purpose set forth comprising a casing, a fluid pressure operated piston arranged therein and having an upwardly extending stem, a locking disk within the casing and secured to the stem intermediate the ends of the latter and provided with a depending flange, a resilient element within the casing and bearing against said disk for maintaining it normally in operative position, a latching means carried by the object to be locked and capable of extending through the wall of and into the cylinder and engaged by and held in latching position by said disk, and means for supplying motive fluid to shift the piston whereby the disk is moved so that its flange clears the latching means, and means within the casing for limiting the release movement of the locking disk.

2. A locking mechanism for the purpose set forth comprising a casing, a fluid pressure operated piston arranged therein and having an upwardly extending stem, a lock-

ing disk within the casing and secured to the stem and provided with a depending flange, a resilient element within the casing and bearing against the disk for maintaining it normally in operative position, a latching means carried by the object to be locked and capable of extending through the wall of and into the cylinder and engaged by and held in latching position by said disk, and means for supplying motive fluid to shift the piston whereby the disk is moved so that its flange clears the latching means, and means within the casing for limiting the release movement of the locking disk.

3. A locking mechanism for the purpose set forth comprising a casing, a fluid pressure operated piston arranged therein and having an upwardly extending stem, a locking disk within the casing and secured to the stem and provided with a depending annular flange, a resilient element within the casing and bearing against said disk for maintaining it normally in operative position, a latching means carried by the object to be locked and capable of extending through the wall of and into the cylinder and engaged by and retained in latching position by the flange of said disk, means for supplying motive fluid to shift the piston whereby the disk is moved so that its flange clears the latching means, and means within the casing for limiting the release movement of the locking disk.

In testimony whereof I affix my signature.

MIKE ZEBICH.
